UNITED STATES PATENT OFFICE.

ELMER L. BRILLHART, OF LUDINGTON, MICHIGAN.

AERONAUTIC TOY.

No. 833,504.

Specification of Letters Patent.

Patented Oct. 16, 1906.

Application filed August 21, 1905. Serial No. 275,134.

To all whom it may concern:

Be it known that I, ELMER L. BRILLHART, a citizen of the United States, and a resident of the city of Ludington, in the county of 5 Mason and State of Michigan, have invented certain new and useful Improvements in Aeronautic Toys; and I do hereby declare that the following is a full, clear, and exact description of the same, reference being had 10 to the accompanying drawings, and to the letters of reference marked thereon, which form a part of this specification.

This invention relates to improvements in aeronautic toys, and more particularly to a 15 toy adapted to elevate and for a time support itself in the atmosphere.

The object of the invention is to afford a toy of cheap, simple, and durable construction and capable of elevating itself to a considerable height and which having attained 20 its maximum height is adapted to be partly supported on the atmosphere to retard its descent.

It is also an object of the invention to afford a construction adapted to be sold at a small price and to afford, in connection with a suitable parachute, a propelling mechanism capable of lifting itself against gravity.

The invention consists in the matters hereinafter described, and more fully pointed out and defined in the appended claims.

In the drawings, Figure 1 is an enlarged side elevation of a device embodying my invention. Fig. 2 is an enlarged fragmentary 35 detail of a part of the motor. Fig. 3 is an enlarged vertical section, partly broken, showing the parachute closed. Fig. 4 is a fragmentary top plan view of the same. Fig. 5 is a section taken on line 5 5 of Fig. 1. Fig. 40 6 is a view similar to Fig. 3, but showing a different support for the parachute.

As shown in said drawings, A indicates a shaft or standard, conveniently a light tube of thin metal, having secured at its upper end 45 a fan comprising radial obliquely-set lifting-blades B, as shown four in number, though obviously any desired number may be used, and by the revolution of which by said shaft A the device is lifted. Said shaft A extends 50 rotatively through a casing C at the lower end thereof. Said casing, as shown, is formed of metal stamped to afford a spider or cage which supports the motor. Said motor, as shown, comprises a coiled spring c, 55 positively secured upon a clutch member c' at its inner end and at its outer end secured on the

arm c² of the casing. Extending through said clutch member c' and the spring and through and rotatably engaged with the bottom of the casing is a winding stud or shaft 6c c³. The winding stud or shaft c³ is rigidly secured in said clutch member c' and extends through a gear c⁴ on the inner side of the casing and on the end of which, extending through the casing, is a clutch member c⁵, 65 complementary with the clutch member c' and adapted to rotate said gear on the winding-shaft by the action of said spring. Said gear c⁴ intermeshes with a pinion c⁶, journaled upon a shaft c⁷, secured in the casing, and is 70 integrally connected with a gear c⁸ on the same shaft. Said gear c⁸ intermeshes with a pinion c⁹, journaled in the top of the casing integral with a gear c¹⁰, which in turn intermeshes with a gear c¹¹, secured on the inner 75 end of the shaft A. Said motor rotates the shaft at a high rate of speed relatively to the rotation of the gear c⁴. Secured axially of and in the top of said shaft A is a spindle a of much smaller size, having secured thereon 80 at its top a parachute of any suitable light fabric or material a', which may be of any desired size or shape. Said parachute, as shown, is connected at intervals around its margin, by means of cords a², with a ring or 85 collar a³, secured on said spindle and which acts to limit the upward and outward movement of the margins of the parachute when the weight of the device is supported in the atmosphere. 90

The operation is as follows: Having wound up the motor, producing a maximum tension upon the spring, the device is supported loosely upon the hand or upon any suitable support, and the motor acts to rapidly revolve the shaft A, whereby the fan B acts to elevate the device to any height, dependent upon the strength of the spring, the speed of rotation, and weight of the device. It is obvious that the parachute remains folded together, as shown in Figs. 3 and 4, with the spindle revolving therein, and presents practically no resistance in the atmosphere during the upward movement. When the motor has nearly expended its energy and the 95 device begins slowly to sink, the upward pressure beneath the parachute spreads the same, as shown in Fig. 1, while the remaining energy of the motor aids in supporting the same, prolonging the flight of the device. 100 Ordinarily the motor is constructed, as shown, with radial arms C' extending beyond

the motor-frame, the plane of which extends parallel with the axis of the shaft and which, though very light, acts to prevent rotation of the motor. As shown in Fig. 5, a skeleton or frame D is supported at the upper end of the shaft A, upon which the parachute is folded inwardly, the cords thereof being attached to upwardly-directed arms a. The parachute in this construction operates as before described, a slightly-descending movement acting to spread the parachute by the upward pressure of air from beneath the same and through the skeleton frame.

While I have shown but one construction for this invention, I do not purpose limiting this application for patent otherwise than necessitated by the prior art, as many details of construction and operation may be varied without departing from the principle of my invention, and obviously any desired material and proportions of parts may be used, as desired.

I claim as my invention—

1. An aeronautic device comprising a motor, a vertical shaft driven thereby, inclined radial fans thereon set to lift the device when the shaft is rotated and a parachute journaled in the top of said shaft and normally folded during the ascent.

2. An aeronautic device embracing a revolute shaft, a fan rigidly secured thereon comprising radial blades or arms set obliquely to raise the device, means rotating the shaft, a non-rotatable spindle extending from the top of said shaft and a parachute supported thereon and closed during ascent.

3. An aeronautic device embracing a revolute shaft, a fan rigidly secured at the upper end thereof comprising radial arms, set obliquely to lift the device, a spindle supported rotatably on the upper end of and in axial alignment with the shaft, a parachute carried on said spindle, a motor for driving said shaft and radial ribs or vanes on the motor-case holding the same from rotation.

4. In an aeronautic device, a casing, a revolute shaft therein, a spring carried in said casing, a clutch connecting the same with said shaft, a parachute and a frame on the end of said shaft affording a support for the parachute.

In testimony whereof I have hereunto subscribed my name in the presence of two subscribing witnesses.

ELMER L. BRILLHART.
